UNITED STATES PATENT OFFICE.

CHARLES D. SHEPARD, OF PEEKSKILL, NEW YORK, ASSIGNOR TO WILLIAM M. CRANE COMPANY, OF PEEKSKILL, NEW YORK.

DESIGN FOR AN ANDIRON.

SPECIFICATION forming part of Design No. 36,149, dated December 2, 1902.

Application filed September 2, 1902. Serial No. 121,910. Term of patent 7 years.

To all whom it may concern:

Be it known that I, CHARLES D. SHEPARD, a citizen of the United States, and a resident of Peekskill, in the county of Westchester and State of New York, have invented a certain new, original, and ornamental Design for an Andiron, of which the following is a specification.

Referring to the drawing, which comprises a part of this specification, the figure is a front elevation of the design for an andiron.

The design consists of a plain shaft or column presenting unbroken side lines and bearing ornamentation in relief, as shown. The column terminates at the top in a rounded knob, with a square offsetting base and a circlet of ovaled reeding. On each side of the column, just below the reeding, a ring bearing leaf ornamentation is integrally joined to it. At the bottom of the column is a representa-

tion of an apophyge, and the base, with scroll ornamentation in relief, divides into spreading branches that terminate in return-scrolls forming feet, a part of the scrolls forming fanciful heads. These branches narrow as they lengthen and have a row of balls along a groove in their central surfaces, the groove and balls diminishing in size in proportion to the narrowing of the branches, all as shown.

What I claim is—

The ornamental design for an andiron substantially as herein shown and described.

Signed at Peekskill, in the county of Westchester and State of New York, this 18th day of August, A. D. 1902.

CHARLES D. SHEPARD.
